FLUSH TANK BALL SEAT

Filed Oct. 27, 1923

FIG. 1.

FIG. 4.

FIG. 2.

FIG. 3.

Inventor
P.B. Hale

By *A. Randolph Jr.* Attorney

UNITED STATES PATENT OFFICE.

PRATT B. HALE, OF ALBANY, ALABAMA.

FLUSH-TANK BALL SEAT.

Application filed October 27, 1923. Serial No. 671,175.

The object of the present invention is to provide a flush tank fixture which admits of the usual ball seat being readily replaced when worn at a small expense, thereby obviating the waste of water and the expense incident to replacing the fixture by a new one.

Other objects and advantages will be apparent and suggest themselves as the nature of the invention is understood.

10 While the drawings illustrate an embodiment of the invention it is to be understood that in adapting the same to meet different conditions and requirements, various changes in the form, proportion and 15 minor details of construction may be resorted to without departing from the nature of the invention.

Referring to the accompanying drawings forming a part of the application:

20 Figure 1 is an elevational view of a flush tank fixture embodying the invention having parts broken away to show more clearly the renewable ball valve seat,

Figure 2 is a side view of the removable 25 seat,

Figure 3 is a top plan view of the seat, and

Figure 4 is a sectional view of a modified form of seat.

30 Corresponding and like parts are referred to in the following description and designated in the several views of the drawings by like reference characters.

The flush tank fixture illustrated is of 35 ordinary construction with the exception of the change whereby the seat for the ball valve is made renewable. The fixture comprises a base 1 having a coupling end 2 and lateral extension 3 to which is fitted the

40 overflow pipe 4. In accordance with the present invention, the opening of the base 1 usually closed by means of a ball valve 5,

is internally screw threaded as indicated at 6 and receives a seat 7 which is externally screw threaded as indicated at 8 to match 45 the screw threads 6 of the base 1. The seat 7 flares upwardly and is recurved at its upper edge as indicated at 9 to extend over the upper edge of the base 1 in line with the opening thereof. The seat 7 is preferably 50 constructed of hard rubber although it may consist of any material suitable for the purpose and not affected by moisture.

The seat 7^a illustrated in Figure 4 has a depending flange 10 and the space 11 55 formed between the flange 10 and the body of the seat is adapted to receive a cementing material such as white lead or putty, this form of seat being provided for ordinary flush tank fixtures devoid of the inner 60 screw threads 6.

The present invention admits of renewing the seat of a flush tank fixture at a comparatively small cost and enables the replacement to be effected by the average person 65 without requiring the services of a skilled mechanic or the replacement of the fixture as a whole.

What is claimed is:

A flush tank fixture comprising an upwardly and outwardly flaring annular wall provided with attaching means, said wall having an outer marginal flange at its upper edge, a lateral extension integral with said wall adapted for connection of an overflow 70 pipe thereto, and a removable valve seat substantially of rubber screw threaded to the inner surface of said wall and having a flange adapted to hook over said flange, said valve seat being adapted to receive a 75 80 ball valve.

In testimony whereof I affix my signature.

PRATT B. HALE.
